UNITED STATES PATENT OFFICE.

CHARLES H. PEDDRICK, JR., OF NEW YORK, N. Y.

DESIGN FOR A TIP FOR UMBRELLA OR PARASOL RIBS.

SPECIFICATION forming part of Design No. 28,562, dated May 10, 1898.

Application filed March 15, 1898. Serial No. 673,982. Term of patent 3½ years.

To all whom it may concern:

Be it known that I, CHARLES H. PEDDRICK, Jr., of New York city, (borough of Manhattan,) county of New York, in the State of New York, have invented and produced a new and original Design for a Tip for Umbrella or Parasol Ribs, of which the following is a full, clear, and exact specification.

Reference is to be had to the accompanying drawing, forming a part of this specification, in which the figure is a perspective view of a tip, showing my design.

The leading feature of my design consists of a bead C, arranged on the tip A, between the base and apex ends thereof. 15

I claim—

The design for the tip of an umbrella or parasol rib, substantially as shown and described.
